ROAD ROLLER

Edward D. Ekenstam, Los Angeles, Calif., assignor
of one-half to Southwest Paving Company,
Los Angeles County, Calif., a corporation of
California

Application October 15, 1945, Serial No. 622,303

11 Claims. (Cl. 94—50)

1

The present invention relates to a novel road rolling machine in which the force-exerting wheels or rollers are arranged so as to make contact with the surface undergoing treatment along substantially a single continuous line extended transverse to the direction of travel. More specifically the invention comprises a road rolling machine in which the force-exerting wheels or rollers are operative upon the surface being treated and are all rotatable about axes which lie within the confines of the wheel of maximum diameter to provide maximum weight concentration.

The use of massive rollers in the surfacing of roads has long been a familiar sight. These rollers are usually one of two types. One type comprises a relatively small diameter front roller or drum and two relatively large diameter spaced rear rollers or wheels, all of great weight. The body of the machine is supported by the axle between the large diameter rear rollers and the front roller, suitable turning means being provided by which the front roller is twisted to change the direction of travel. The second type comprises the two roller type in which a small turnable front roller is combined with a larger diameter rear roller, the body of the machine being supported therebetween.

The present road rolling machine comprises an improvement upon these earlier and bulkier machines. In the road roller constructed in accordance with the present invention, the mass which provides the weight to compress the surface being treated is suspended below the single main axis of the machine, being supplemented by the weight of the rollers themselves. The two principal surface-contacting rollers or wheels are rotatable about this main axis and a third smaller diameter roller rotates about an axis positioned therebelow and within the circumferential projection of the main rollers. The driving means for the machine comprising a suitable engine mounted within the confines of these main rollers, and the platform from which the operator controls the machine are positioned immediately above the rollers and mounted so as to be substantially horizontal in all positions of the rotating rollers. The construction is relatively simple and has the inherent advantage of exerting all of its weight along a single line of contact rather than dividing the weight between two or more lines of contact as in the earlier machines.

It is an object of the present invention to provide a new and simplified road rolling machine having features not found in earlier and more cumbersome machines.

2

It is another object of the invention to provide a road rolling machine which is capable of operating immediately adjacent to vertical walls and curbs, thereby eliminating the necessity for manual tamping.

5 A further object of the invention is to provide a road rolling machine which can be turned in a very small radius and which is operative in places inaccessible to earlier machines.

10 A still further object of the invention is to provide a new type road rolling which supplements the rolling capabilities of the preceding types and which is particularly adapted to work on driveways, tennis courts and similar spaces of limited area.

15 Referring now to the drawings in which a preferred embodiment of the invention is disclosed:

Fig. 1 is a view in perspective of a road roller constructed in accordance with the present invention;

20 Fig. 2 is a partial view in perspective of one of the masses which gives to the machine its weight for its rolling function and which provides a counterbalance for the seat-carrying platform;

25 Fig. 3 is a vertical section through the machine upon the line 3—3 of Fig. 1 and discloses the power-transmitting belts which function as clutches and also the manually operable control means therefor;

30 Fig. 4 is a horizontal section upon the line 4—4 of Fig. 3 and shows the power-transmitting means;

Fig. 5 is a transverse vertical section upon the line 5—5 of Fig. 4;

35 Fig. 6 is a similar section but upon the line 6—6 of Fig. 4; and

Fig. 7 is a longitudinal vertical section through the machine upon the line 7—7 of Fig. 6.

The road roller constructed in accordance with the present invention comprises two large diameter main rollers 1 and 2 of heavy metal which are rotatable about the same longitudinal axis and between which is positioned a smaller roller 3 which is so constructed and arranged as to exert substantially the same downward force per unit of surface-contacting area as do the larger rollers. The large diameter rollers 1 and 2 are identical, and it is necessary to describe only one of them. Roller 1 is seen to comprise a permanently connected rigid end plate or cap 4 formed with a central cup portion 6 which seats a roller bearing 7 secured by a nut 8 upon the screw-threaded reduced end of the main shaft 9. The rollers 1 and 2 are open interiorly but are closed at their outer sides by the end plates 4.

While these rollers or drums are made of exceedingly heavy and strong metal and are rigid, it is nevertheless desirable to provide bearing supporting means at their adjacent ends, and these means are provided by radially extending spiders or arms 11 which at their central junction carry a sleeve bearing 12 which rotatably seats upon the shaft 9. Rollers 13 at the outer ends of arms 11 are formed with peripheral channels which ride upon a guide ring or band 14 permanently affixed to the interior surface of the roller rim.

While the rollers or wheels 1 and 2 are exceedingly heavy, it is desirable that they exert even greater weight downwardly upon the surface being treated. To provide this additional weight, and to maintain the machine in an erect position, counterweights 16 and 17 are provided, one being positioned within the confines of each roller. Weights 16 and 17 are connected by rods 18 at their adjacent sides where each is also connected, as by a plurality of rivets 19, to the lower pair of arms 11.

Formed integrally at the outer sides of each of the weights 16 and 17 is an enlarged bearing cup 21 which encloses the outer race of a bearing 22, the inner race of which seats upon the cup 6 formed in the roller end plate 4. The ball bearings 22 and the sleeve bearings 12, positioned at the opposite sides of each roller, provide means by which weights 16 and 17 are enabled to remain in their lowermost position below the supporting axle 9 and independent of the rotation of the rollers 1 and 2 and also independent of any rotation of the shaft 9.

The smaller intermediate roller or wheel 3 is seen most clearly in Fig. 7 to be positioned longitudinally between the larger rollers 1 and 2 and to be rotatably mounted by means of a shaft 23 and bearings 24, each bearing being positioned in a block 26 slidably seated in an arcuate groove or seat 27 formed in the weight 16. Blocks 26 at the ends of the shaft 23 are adapted to slide in their supporting channels 27 so that regardless of the position of the weights within the supporting rollers 1 and 2, the central roller 3 may at all times move relative thereto so that its peripheral surface will rest upon the underlying roadway.

The driving motor for the road roller constructed in accordance with the present invention is positioned within one of the main rollers and, in the illustrated embodiment, within roller 1. The motor is indicated generally by the reference character 31 and is seen to be carried by brackets 33 secured to the adjacent bearing cup 21 of the mass 16. The motor 31 may be of any well known type, such as gasoline or Diesel, and includes a clutch 34 and a multi-speed transmission 36. The drive shaft 37 carries a sprocket gear 38 which is connected by a chain 39 to a gear 41 affixed to and rotatable with main shaft 9. Gear housings 42, formed of spaced side walls 43, are carried at the inner sides of each of the rollers 1 and 2 by the spider arms 11. The gearing within these housings is identical and only the unit for the roller 1 will be described.

Within the gear housing 42 of roller 1 is positioned a driven gear 44 carried by shaft 9 and which meshes upon its opposite sides with gears 47 and 48. The shafts 49 of these two gears extend through the walls 43 of the gear box 42, and each carries a pulley 51 which is keyed thereto. A power-transmitting belt 52 connects pulley 51 of gear 47 to a forward pulley 53 which is keyed to the shaft 54 of a pinion 56, while the

belt 52 driven by gear 48 drives the pulley 53 carried by a shaft 54 supporting a pinion 57. Forward pinion 56 meshes directly with a ring gear 58 mounted upon the inner peripheral surface of the roller 1, while pinion 57 is spaced from ring gear 58 and instead meshes with a second pinion gear 61, carried by a shaft 62, which in turn meshes with the ring gear 58.

It is clear from a consideration of the gear trains that pinions 56 and 57 rotate in the same direction while pinion 61 rotates in the opposite direction. It follows that only one of the belts 52 of the pair of belts connected to either roller 1 or 2 can transmit power at any one time. Accordingly, belts 52 are adapted to ride freely upon the driven pulleys 53 in the absence of a tension which may be placed therein by the operator by suitable means which comprise at the belt end idler pulleys 66 and 68 suitably mounted upon levers 67 and 69. The application of a belt-tensioning force by the idler pulley 68 carried by lever arm 69 causes the pinion 53 meshing directly with the ring gear 58 to be operated. With the main shaft 9 rotating in the direction of the arrows indicated in Figs. 3 and 6, the roller 1 will be driven in a counter-clockwise direction and the machine will move rearwardly. With tension applied through idler pulley 66 to the belt 52 which results in the rotation of the pinion gear 61 the roller 1 will be driven in a clockwise direction, as viewed in Figs. 3 and 6, and the machine will move forwardly. As previously stated, the power transmitting and control means for the individual rollers 1 and 2 are identical.

The operator's platform on the top of the machine is indicated by the reference character 71 and is seen to carry the driver's seat 72 and to be supported by means of a plurality of strap brackets 73 which extend downwardly from the platform between the rollers 1 and 2 to be secured at their overturned lower ends to the top surfaces of the weights 16 and 17. The strap brackets are clearly illustrated in Fig. 2 in connection with the weight 16, and it is to be noted that the weights being suspended below the axle 9, function as counterweights to hold the platform 71 in its position above the rollers. A plurality of control levers extend upwardly through the platform 71 to position adjacent the driver's seat 72 including manually operable levers 74 and 76 rigidly connected to the levers 67 and 69, respectively, which carry the idler pulleys 66 and 68. Levers 74 and 76 are biased forwardly by springs 78, one of which is shown in Fig. 3. The exertion by the operator of a rearward force upon either of these two levers causes that roller, either 1 or 2, to be driven in a clockwise direction, as viewed in the drawings; that is, causes the machine to move forwardly. Levers 74 and 76 are therefore the forward control levers. Foot pedals 77 and 78 are rigidly connected to the levers 69 carrying the idler pulleys 68, and a forward force exerted upon either causes the belt 52 to be tightened and rotate the forward pinion 54 which meshes with the ring gear 58. Thereupon, the machine would move rearwardly. Pedals 77 and 78 are spring-biased rearwardly by springs 75, as illustrated in the case of pedal 77 in Fig. 3.

In addition to the afore-described control means available to the operator on his platform 71 is a clutch lever 81 and a gear shift lever 82 which are connected to the transmission 36 and the clutch 34, respectively, of the driving motor 31 and which perform the control operations

indicated by their names in the common and well known manner characteristic of the automobile. There is also provided, and in a position readily available to the driver, a motor-speed controller 83 by which the revolutions per minute of the motor 31 can be controlled in order to increase or decrease the speed of the machine.

To aid in the removal of foreign material which inevitably adheres to the road-contacting surfaces of the rollers 1 and 2, there are provided water-containing reservoirs 86 below the platform 71 and above the rollers. Scrapers 87 extend downwardly from the lower extremities of these containers into scraping contact with the roller surfaces, and apertures 88 provide for the escape of water from the containers onto the adjacent surface to aid in the dislodgment of the material. As the small diameter central roller 3 is not contacted by the scrapers 87, it is provided with its own individual scrapers 91 carried by the weight-connecting arms 18 previously described.

The operation of the road roller constructed in accordance with the present invention is as follows:

Let it be assumed that the driving motor 31 is turning over, having been started by suitable starting means which form no part of the present invention and which may be of any ordinary and well known type. Let it also be assumed that the motor-controlling clutch lever 81 is in the neutral position and that the roller-controlling levers 74 and 76, and pedals 77 and 78, are in their inoperative positions in which no power is transmitted by the driving belts 52 and the machine is standing still.

The operator desiring the machine to move forwardly first operates the motor clutch lever 81, much as the clutch pedal is operated in the ordinary automobile, and moves it to clutch-open position and then shifts the gear shift lever 82 into its low speed position. The operation of the motor and the closing of the clutch 34 causes the motor shaft 37 to rotate at a speed determined by the setting of the gear shift lever 82. Shaft 37 rotates pinion 38 which through the chain 39 drives the gear 41 and the shaft 9 rotates in its bearings 7 entirely free from the rollers. The gears 44 of course rotate with the shaft 9 to drive the gears 47 and 48 and make available the motor's power at the pulleys 51 which seat the belts 52. By pulling rearwardly upon the levers 74 and 76, the operator tensions the belts 52 which drives the pinion gears 61 to cause the rollers 1 and 2 to rotate clockwise, as viewed in the drawing, to move the machine in the forward direction. As the machine picks up speed, the operator operates the motor clutch lever 81 and the gear shift lever 82 to shift the motor into high speed operation in the common and well known manner characteristic of automobiles. Obviously, if he desires, the operator can retain the motor at any speed of operation.

Let it now be assumed that the operator desires to turn the machine slightly to the right or to the left. As viewed in Fig. 1, if the operator desired to turn to the left, he would release the pull upon the lever 74 while holding it upon the lever 76. The roller 2 would continue to be driven by its tensioned belt 52 while roller 1 would lose its driving force as its belt 52 lost its tension. With driving force present only in wheel 2 the unit would turn to the left. By causing rollers 1 or 2 to rotate simultaneously

or selectively, the operator can cause the unit to move in a straight line or in a curved path. Should the operator desire to reverse the direction of travel, he releases the forward control levers 74 and 76 and instead exerts pressure upon the pedals 77 and 78. As previously described, this tensions those belts 52 which causes the pinion 56, in direct contact with the ring gear 58, to rotate and the machine moves rearwardly. Turning the machine while moving in the rearward direction is analogous to turning when moving forwardly, the difference being only in that the foot pedal 77 and 78 are operated rather than the hand levers 74 and 76. It will also be evident that the machine may be spun on its vertical axis by causing one of the rollers 1 and 2 to move forwardly and one of said rollers to move rearwardly.

In all movements of the machine, the central roller 3 rides along upon the surface between rollers 1 and 2. Assuming even a very steep incline in which the massive counterweights 16 and 17 would be angularly spaced relative to a plane through the axle 9 and the line of surface contact of the rollers 1 and 2, it is still possible for roller 3 to ride in contact with the surface, for its supporting shaft 23 is free to move, its bearing-carrying blocks 26 being slidable 35 along the guideways 27 formed in the weights 16 and 17.

The rolling machine constructed in accordance with the present invention is characterized in that there are no laterally extending portions or extra or other balancing means outside the horizontal extensions of the rollers, as is clearly evidenced from a consideration of Fig. 7. The rollers 1 and 2 can move up against and into contact with a vertical wall to compress the roadway surface adjacent thereto, thereby eliminating all necessity for manual tamping. As previously mentioned, the entire weight of the machine is concentrated within a small space to act vertically downwardly at the line of surface contact to insure that the greatest possible compressing force will be exerted for a given weight.

While the particular apparatus herein shown and described in detail is fully capable of attaining the objects and providing the advantages hereinbefore stated, it is to be understood that it is merely illustrative of the presently preferred embodiment of my invention, and that I do not mean to limit myself to the details of construction or design herein shown, other than as defined in the appended claims.

I claim:

1. A road rolling machine comprising a pair of spaced heavy rollers, a main shaft about which said rollers are rotatable and which maintains them spaced and in alignment, weights positioned within said rollers and suspended from said shaft, with each weight being provided with a vertically extending slot, a small diameter idler roller positioned between said spaced rollers with its shaft slidably mounted in said slots to enable it to contact supporting surfaces of various inclinations, a platform positioned above said rollers, and brackets extended between said spaced rollers and supporting said platform on said weights, whereby said platform is maintained in a substantially horizontal position.
2. A rolling machine which includes: a shaft; a plurality of rollers rotatably mounted on said

shaft; a motor; transmission means for imparting rotation from said motor to said shaft; a ring gear provided on the interior surface of each of said rollers; gear advancing and reversing means engaging each of said ring gears; a plurality of driving gears supported on said shaft; a pair of driven gears engaging each of said driving gears; belt means connecting each of said gear advancing and reversing means with one of said driven gears; vertically extending lever means for regulating the tension on each of said belt means whereby said rolling machine may advance or reverse and be guided by varying the speed of rotation of each of said rollers; a plurality of weights, with each of said weights non-rotatably supported from said shaft in one of said rollers; a vertically movable shaft disposed between each two of said weights; and an idling roller rotatably mounted on each of said vertically movable shafts.

3. A rolling machine which includes: a plurality of rollers; a motor; a variable speed power transmitting means between said motor and said rollers, with each of said rollers adapted to rotate at a speed independent of the speed of the balance of said rollers; operator supporting means; a weight non-rotatably supported inside said rollers, and with said operator supporting means affixed thereto, said weight being sufficiently heavy to act as a counterbalance in maintaining said operator supporting means in a substantially predetermined position; means for controlling said power transmitting means positioned operable from said operator supporting means, whereby the operator may guide said rolling machine by varying the speed of rotation of said rollers; a vertically movable shaft supported between each two of said weights; and an idling roller rotatably mounted on each of said vertically movable shafts.

4. A rolling machine which includes: a shaft; a plurality of rollers rotatably mounted on said shaft; a motor; transmission means for imparting the rotation of said motor to said shaft; independent variable speed transmission means between said shaft and each of said rollers; an operator's platform, a weight non-rotatably supported inside said rollers, and with said platform affixed thereto, said weight being sufficiently heavy to act as a counterbalance in maintaining said platform in a substantially horizontal position; and lever means operable from said platform adapted to control said variable speed transmission means whereby the operator may guide said rolling machine from said platform; a vertically movable shaft supported between each two of said weights; and an idling roller rotatably mounted on each of said vertically movable shafts.

5. A rolling machine which includes: a shaft; a pair of rollers rotatably mounted upon said shaft; a motor; transmission means for imparting the rotation of said motor to said shaft; independent belt transmission means between said shaft and each of said rollers; an operator's platform; a weight non-rotatably supported inside said rollers, and with said platform affixed thereto, said weight being sufficiently heavy to act as a counterbalance in maintaining said platform in a substantially horizontal position; and lever means operable from said platform for regulating the tension on each of said belt transmission means whereby the speed of rotation of each of said rollers may be varied and said rolling machine guided; a freely rotatable idling roller disposed between said rollers; a vertically movable

shaft for said idling roller to rotate on, with said shaft being supported from said weight.

6. A rolling machine which includes: a shaft; a plurality of rollers rotatably mounted on said shaft; a motor; transmission means for imparting rotation from said motor to said shaft; a ring gear provided on the interior surface of each of said rollers; gear advancing and reversing means engaging each of said ring gears; a plurality of driving gears supported on said shaft; a pair of driven gears engaging each of said driving gears; belt means connecting said gear advancing and reversing means with said driven gears; weight means non-rotatably contained inside said rollers; an operator's platform supported from said weight means and adapted to be held in a substantially horizontal position thereby; means operable from said platform for regulating the tension on each of said belt means whereby said 20 rolling machine can be made to advance or reverse and be guided by varying the speed of rotation of each of said rollers; an idling roller disposed between each two of said rollers; and a vertically movable shaft mounting for each of said idling rollers.

7. A rolling machine which includes: a plurality of spaced rollers; a motor; a variable speed power transmitting means between said motor and said rollers, with each of said rollers adapted to rotate at a speed independent of the speed of the balance of said rollers; a weight non-rotatably supported in each of said rollers; a vertically movable shaft supported between each two of said weights; an idling roller rotatably supported on each of said shafts; operator supporting means affixed to said weight and held in a substantially predetermined position thereby; and means for controlling said power transmitting means positioned operable from said operator supporting means whereby the operator may guide said rolling machine by varying the speed of rotation of said rollers.

8. A rolling machine which includes: a plurality of spaced rollers; a motor; a variable speed power transmitting means between said motor and said rollers, with each of said rollers adapted to rotate at a speed independent of the speed of the balance of said rollers; a weight non-rotatably supported from said shaft in each of said rollers, with the ends of each of said weights being provided with a vertically extending channel; a shaft extending between each of said weights and vertically movable in said channels; an intermediate roller rotatably supported on each of said shafts to provide said machine with full rolling contact with the roller surface; operator supporting means affixed to said weight and held in a substantially predetermined position thereby; and means for controlling said power transmitting means positioned operable from said operator supporting means whereby the operator may guide said rolling machine by varying the speed of rotation of each of said motor driven rollers.

9. A road rolling machine which includes: a pair of spaced rollers; a motor; a variable speed power transmitting means between said motor and said rollers, with each of said rollers adapted to rotate at a speed independent of the speed of the opposite rollers; a weight non-rotatably supported inside each of said rollers; a shaft movably supported between said weights; an intermediate roller rotatably supported on said shaft and providing said machine with full rolling contact with the rolled surface; and means for con-

trolling said power transmitting means whereby the speed of rotation of each of said motor driven rollers may be varied and said rolling machine guided.

10. A rolling machine which includes: a shaft; a pair of spaced rollers rotatably mounted on said shaft; a motor; transmission means for imparting the rotation of said motor to said shaft; independent variable speed transmission means between each of said rollers and said shaft; a weight non-rotatably supported in each of said rollers; a vertically movable shaft supported between said weights; an intermediate roller rotatably mounted on said weight supported shaft and providing said machine with full rolling contact with the rolled surface; and means for operating said variable transmission means whereby the speed of rotation of each of said motor driven rollers may be varied and said rolling machine guided.

11. A rolling machine which includes: a shaft; a pair of laterally spaced rollers rotatably mounted on said shaft; a pair of segmental cylindrical shaped weights, each of said weights being disposed inside one of said rollers and non-rotatably supported from said shaft; a substantially horizontal shaft movably supported between said weights; an intermediate roller rotatably supported on said shaft; a motor rigidly supported from one of said weights; chain transmission means for imparting rotation from said motor to said shaft; a ring gear provided on the interior surface of each of said rollers; gear advancing and reversing means engaging each of said ring gears; a pair of driving gears supported on said shaft; a pair of driven gears engaging each of said driving gears; belt means connecting said gear advancing and reversing means with said

driven gears; a pair of spiders for reinforcing said rollers, each of said spiders being affixed to one of said weights and having a plurality of radially extending arms; a plurality of rolling members, each of said rolling members being rotatably supported from one of said arms and engaging the interior surface of one of said rollers; an operator's platform supported from said weights and held in a substantially horizontal position thereby; and lever means operable from said platform for regulating the tension on each of said belt means whereby said rolling machine may be advanced, reversed or guided by varying the relative speed of rotation of said motor driven rollers.

EDWARD D. EKENSTAM.
